J. BING

ELECTROMAGNETIC CHUCK

Filed June 3, 1924

Inventor:

Julius Bing

By his Atty, Harold D. Penney

Patented Oct. 30, 1928.

UNITED STATES PATENT OFFICE.

JULIUS BING, OF EISENACH, GERMANY, ASSIGNOR TO MAGNET-WERK G. M. B. H.,
EISENACH, SPEZIALFABRIK FÜR ELEKTROMAGNET-APPARATE, OF EISENACH,
GERMANY.

ELECTROMAGNETIC CHUCK.

Application filed June 3, 1924, Serial No. 717,657, and in Germany June 5, 1923.

This invention has reference to means of producing a tight and water-proof packing for electromagnetic chucks or work holding apparatus by means of which moisture is excluded from coming in contact with the magnetizing coils of said devices. In the electromagnetic chucks heretofore in use it has been found to be practically impossible to so mount the coil or coils in the apparatus as to protect them from moisture. The manner of imbedding the coils usually employed by casting a resinous or similar compound around them, while being sufficient to prevent the entrance of the particles of water which are liable to find their way through the crevices and joints of the magnet casing for some time, does not constitute a permanent protection, inasmuch as the compound loses its plasticity by the frequent heating, thereby producing capillary crevices through which the water finds an easy entrance and causes short-circuiting and earthing.

In accordance with this invention the difficulties referred to are avoided by employing oil as an insulating agent. Inasmuch as the entering water is heavier than oil it will descend and collect at the bottom of the container. In order to prevent its coming in contact with the coil or spool, means are provided to mount the spool in a box with open top disposed in the winding chamber of the apparatus, the said box being closed by a suitable cover, preferably provided with an upwardly tapering, laterally outwardly extending roof shaped portion.

The invention in a preferred form of construction, embodying an exemplification of the principles of the invention, is shown on the accompanying drawing in a somewhat conventional manner in sectional view through the chuck.

In the drawing *a* is the shell or casing forming the magnet body of the apparatus which is provided with the usual annular winding chamber surrounding the core *i* of the magnet. In this chamber *b* a ring shaped box *c* of sheet metal or the like and in the construction shown by way of example, with open top is provided in which the energizing spool or coil *d* is mounted in any suitable manner. The cover *e* for closing this box is roof shaped, and possesses outwardly protruding edges *f*. *k* is the top or work holding plate which in the usual way is formed

with slots filled out with non-magnetic material such as brass. The top plate *k* is secured to the shell or magnet body *a* in the usual way.

In view of this construction any entering water will flow off along the teetiform closing member, and may collect at the bottom of the winding chamber *b*, whence it may be discharged through the conduit or hole *g*. The downwardly projecting flange *f* of the cover surrounds the casing and constitutes an additional tightening. Besides the conduit *g* another opening *h* may be provided in the upper portion of the casing, and these two openings *g* and *h* may be used for the purpose of causing a current of cooling agent, water or the like to flow through the casing.

The invention has been shown and described in its broad aspects only, but it is obvious that it is not limited to the particular construction represented by way of exemplification merely, but it is susceptible of various modifications and forms of constructions according to requirements, and without deviating from the spirit of this invention as set forth in the appended claims.

The invention is not restricted to a particular number or shape of winding chambers, and more than one spool or coil may be provided in the apparatus.

I claim:—

1. An electro-magnetic chuck comprising a base of magnetic material provided with an annular channel extending downwardly from its top, a cover plate of magnetic material covering the channel, an annular open topped casing seated in said channel and spaced from the sides and bottom of said channel, a removable annular cover having inner and outer peripheral flanges and of inverted V-shape between said flanges, said cover resting on the open top of the casing with the flanges extending down the sides thereof, and a magnet winding in said casing and having its convolutions extending horizontally through said casing.

2. An electro-magnetic chuck comprising a base of magnetic material provided with an annular channel extending downwardly from its top, a cover plate of magnetic material covering the channel, an annular open topped casing seated in said channel and spaced from the sides and bottom of said channel, a removable annular cover having

inner and outer peripheral flanges and of inverted V-shape between said flanges, said cover resting on the open top of the casing with the flanges extending down the sides thereof, a magnet winding in said casing and having its convolutions extending horizontally through said casing, and an insulating oil filling the space between the winding and

casing walls and the space between the casing and channel walls, said base having normally closed inlet and drain ports communicating with the upper and lower parts of the channel respectively. 10

In testimony whereof I affix my signature.

JULIUS BING.
